UNITED STATES PATENT OFFICE.

VINCENT A. MENUEZ, OF MEMPHIS, TENNESSEE.

VAPOR-LAMP.

SPECIFICATION forming part of Letters Patent No. 655,258, dated August 7, 1900.

Application filed February 24, 1900. Serial No. 6,368. (No model.)

To all whom it may concern:

Be it known that I, VINCENT A. MENUEZ, a citizen of the United States, residing at Memphis, Shelby county, State of Tennessee, have 5 invented certain new and useful Improvements in Vapor-Lamps, of which the following is a specification.

My invention relates in general to improvements in oil or gasolene lamps of the vaporizer type, but especially to that class of such lamps in which the oil is stored in a reservoir, from which it is forced by compressed air or is allowed to flow by gravity through suitable distributing-pipes to the lamps.

15 The objects of my invention are to improve the lamp in general and in detail and at the same time to reduce the cost of the lamps. I accomplish these objects, first, by providing a simple, cheap, and effective extension-tube to permit access to the lamp for lighting and adjustment; second, by providing means for the initial generation of gas; third, by providing an improved mixing-tube; fourth, by providing an improved burner; fifth, by providing an improved shade-holder; sixth, by providing an improved deflecting-cap for the chimney to concentrate the heat from the chimney on the generator; seventh, by providing an improved form of storage-tank; 25 eighth, by an improvement in the construction of the needle-valve, and, last, by the general improvement in details and by the novel combination of parts hereinafter set forth in the specification, drawings, and claims.

35 In the drawings, which show the preferred form of my lamp, Figure 1 is a section on the center line of one of my improved lamps. Fig. 2 is a section on the center line of the upper stuffing-box of the extension-pipe. Fig. 3 is 40 a like section of the lower stuffing-box, showing a slight modification from the same box in Fig. 1. Fig. 4 is a section on the line B B of Fig. 1 to show attachment of the extension-lock. Fig. 5 is a section on the line A A of 45 Figs. 1 and 4 to show locking-spring. Fig. 6 is a plan of the air-inlet of the mixing-tube, looking in the direction of the arrow C, Fig. 1. Fig. 7 is a section of the burner-cap. Figs. 8 and 9 are a plan and section, respectively, 50 of a modification of the burner-cap. Fig. 10 is a section of my improved storage-reservoir, with compressed air to force out the gasolene

and aerate same prior to generation of the gas. Fig. 11 is a view of a double lamp with a modified form of mixing-chamber shown in 55 section. Figs. 12 and 13 are details of a valve. Figs. 14, 16, and 17 are details of the initial generator. Fig. 15 is a detail of the needle-valve. Fig. 18 shows a view of an old form of extension-bracket which may be used. 60 Figs. 19 and 20 are details of the shade-holder. Figs. 21, 22, and 23 are a plan and two sections of the heat-deflector or chimney-cap. Fig. 24 is a form of separate storage-reservoir with attached air-pumps. This reservoir may be placed outside of the buildings 65 or buried in the ground, if desired.

Referring now to the drawings, in which like numerals denote the same or like parts in all the views and confining the description at first to the single-burner lamp shown in Fig. 1, 1 is a hollow curved tube forming one side of the lamp-frame and serving at the same time as a gas-chamber, being virtually the same design as that claimed in my 75 pending application, Serial No. 719,601, filed June 6, 1899. Opposite this tube 1 is a similar tube 2, closed, however, at both the upper and lower ends, which also forms a part of the frame. These tubes are united at their 80 lower ends in a substantially Y-shaped piece 3, which encircles both the pipes 1 and 2 and is brazed to them. At their upper ends these pipes are fastened to a yoke made up of the two tubes 4 and 5, which are in turn joined 85 together in a T 6, into which is also fastened an oil-tube 7, leading to the oil-reservoir 8, Fig. 10, or 8^a, Fig. 24. The pipe 4 is closed by a plug 9 and the oil compelled to flow 90 through the pipe 5 to the generator. After passing through the Y-piece 3 the pipe 1 terminates in a vertical cylindrical portion 10, (see Fig. 11,) the piece 3 forming a collar at the lower end of this vertical portion. Over this vertical cylindrical portion 10 is slipped a 95 burner, made up of a short section of pipe 11, integral with which is an inverted-cup-shaped piece 12, which terminates in a horizontal portion 13, on which the chimney 14 rests. Under this horizontal portion 13 lugs 15 are 100 provided to hold the mantle-support 16 and the chimney-holders 17. The cup-shaped piece 12 has air-holes 18 through it, which holes are opened or closed by a close-fitting

piece 19, having holes which can be turned into or out of register with the holes 18. A perforated cap resting on top of the vertical portion 20 completes the burner. This cap 5 has a series of holes 21 to permit the gas to escape from the gas-chamber to be burned and a deflecting-plate 22 to deflect the flame against the mantle 23. This cap 20 has a series of flutes or corrugations 24, which bring 10 the cap to approximately the size of the mantle 23, as shown in Fig. 8, and at the same time leave spaces 25 to permit the entrance of air between the cap and mantle to steady the mantle and provide air for combustion. 15 Fig. 9 illustrates a modified form of cap 20, in which the deflecting-plate 22^a is sunk in the cap instead of being placed above it, as in Fig. 7. While the holes 21 shown are separate and distinct, it is not essential that such 20 should be the case, the ordinary form of wire-netting caps with the deflecting-plates serving quite as well.

The closed tube 2 terminates at its upper end in a horizontal portion, through which is 25 centrally fastened a generator 65. This generator extends through the bend in the pipe 2 and has a stuffing-box 27 and hand-wheel 28 at the opposite end. This generator 65 extends centrally across the center line of the 30 burner below, by which it is heated, and is here surrounded by a tube 26, which serves as the gas-generator for the lamps. Extending past the center line of the burner the generator 26 terminates in a mixing-chamber 29, 35 which chamber surrounds the upper end of the gas-chamber 1 and the said generator 26, the centers of the generator 26 and this gas-chamber 1 being in line.

A deflecting-cap 30 (see also Figs. 21 to 23) 40 concentrates the heat from the burner on the needle-valve generator 26, while a reflector 31 also helps to concentrate the heat thereon.

The ends of the cylinder 29 are perforated with holes 32, which are closed or opened by 45 the rotation of the cap 33. If desired, this box may be made rectangular in form instead of cylindrical, in which case it is preferably made a cube with the needle-valve and vapor-tube entering opposite sides. Two or more 50 of the free sides or ends of the box may be perforated, as were the ends of the cylinder, and, as in it, the air-opening regulated by the rotation of a perforated circular cap 33. This mixing-chamber may be rotated around the 55 generator 26 and gas-chamber 1 as an axis in case drafts should tend to disturb the flow of air. By rotating this chamber properly the lamp can be placed in an exposed position without danger of any disturbance of this 60 kind.

29^a, Fig. 11, is a modified form of mixing-chamber. This chamber is substantially bell-shaped, and the admission of air is regulated as in the first case.

65 As a means of starting the initial generation of gas in the generator 26 I provide an oil or alcohol-containing receptacle, prefer-

ably filled with asbestos or like non-combustible material which is saturated with combustible fluid, which receptacle is fastened to 70 the under side of the side frame 2 in such manner that it can be brought under the generator without detaching it from the frame 2 and so disposed under the frame 2 that when swung out of use the flame is extinguished 75 by the said frame. I illustrate this heater 34 in two slightly-modified forms. That shown in Fig. 1 is pivoted and swings around into the dotted position 35. The open top is the same as that shown at 36 in Figs. 16 and 17. 80 This opening 36 is closed by the frame 2 when swung under same. In the modified form the heater 34 slides in and out in a hollow tube 37, the flame being extinguished by drawing the heater 34 back into the tube 37. Since 85 the heater 34 when extended is still under the center of the needle-valve, it would be extremely difficult to fill the said heater when it was exhausted. I provide, therefore, a slot 38 near the end of the tube 37, which permits 90 the heater to be rotated to the dotted position shown for filling.

In order to reach the lamp for filling or lighting and to bring it lower for use, if so desired, I provide an extension supply-tube, 95 consisting of an outer tube 7, fastened to the down-tubes 4 and 5 at its lower end and having at its upper end a stuffing-box which slides on an inner tube 39. This inner tube leads to the oil-tank reservoir, from which it may be shut off by a valve 40, and has at its lower end a stuffing-box sliding on the inside of the tube 7. These stuffing-boxes consist of tight collars 41 and 41^a, attached, respectively, to the upper end of the tube 7 and 100 lower end of the tube 39, double flexible packing-washers 42, separated by a loose collar 43, the whole being held by adjustable nuts 44 and 44^a, which force the flexible packing against both tubes. These stuffing-boxes 105 serve the double purpose of stuffing-boxes and guides and prevent the pipe when extended from being displaced and the packing loosened.

When the lamp is pushed to its highest position, being that shown, it is held up by a catch 46, which catches under a collar 45 on the nut 44. This catch 46 is pivoted on a collar 47, clamped to the tube 39, and is held against the collar 45 by a spring 48, also 110 clamped to the collar 47. A cord or wire 49, depending from the other end of the catch 46, serves as a means of releasing the catch when the tube is to be lowered. It will be noted that the collar, Fig. 4, is clamped to the tube 39 and may be adjusted by loosening a cap-screw and sliding the collar to the point desired. This enables the height of the lamp when raised to be adjusted to varying heights of ceiling or other conditions. 115 This form of extension, while described for a vertical drop, may also be used in connection with a bracket fastened to the wall or, in fact, any horizontal pipe as a horizontal ex-

tension, and may be used with gas-lamps of the ordinary type as well as with vapor-lamps, and I wish the claims covering this extension to be read as covering a horizontal as well as 5 a vertical drop and to be not limited to a vapor-lamp, but to include all forms of gas-lamps and brackets as well. As an alternate extension to be used with the other parts of the lamp, if so desired, I show a flexible tube 10 5^a, Fig. 18, connecting the pipes 39 and 7; but no claim is made to this extension in itself, as it is old. It is shown merely to illustrate the fact that I do not wish to confine the use of the other and novel parts shown to one 15 particular form of extension.

Figs. 19 and 20 show a shade-holder, which consists of a band 51, surrounding but not touching the chimney 14, (shown by the dotted lines,) which has three arms 52 cut underneath the band 51 and bent out therefrom. To these arms are riveted the shade-clips 53, having a portion of their lower ends bent out to support the shade and a projection 54 on their side to steady them against the chimney. 25 These shade-holders rest on the chimney at three points 55 and at these points only, thus bringing only three points instead of the entire band in contact with the glass chimney.

30 Fig. 24 illustrates the ordinary form of oil-storage reservoir, in which 8^a is the reservoir, and 56 the air-pump. A pressure-gage and thumb-valve for filling the tank are also shown in the figure. This reservoir may be placed in 35 any part of the building, or, if so desired, may be placed outside of the building or buried in the ground.

Fig. 10 shows a special form of reservoir on the supply-pipe 7. In this view I have shown 40 a lamp without extension, the same being lowered—reservoir and all—for filling. In this view, then, 8 is a storage-tank, 57 is an air-valve adapted to be connected to any ordinary form of air-pump, (not shown,) and 58 a screw-cap to permit filling. The pipe 7 passes entirely through the reservoir 8 and is brazed to it top and bottom. A small pipe 59 starts near the bottom of the oil-reservoir 8 and extends up and into the pipe 7, the joint being 45 brazed where the smaller pipe enters the larger one. In this construction the air above the oil in the reservoir forces the oil upward through the pipe 59 into the pipe where it is partially vaporized and then descends by 50 gravity to the vaporizer or needle-valve generator 26. I thus obtain, with a close-connected reservoir, the advantages of air aeration and at the same time avoid the large shadow inevitably cast by a reservoir placed 55 below the lamp. The air forced into the reservoir over the oil or other hydrocarbon fluids admixes intimately with them in passing downward through the fluid to the mouth of the feed-pipe 59. Air thus intimately associated with a hydrocarbon fluid absorbs some 60 of the fluid in the form of vapor and carries with it other particles mechanically mixed.

It passes upward through the feed-tube 59 and is discharged upward in the tube 7, becoming thus further vaporized. It descends thence 70 through the pipe 7 to the generator 26, where it is converted into gas. I thus secure a mixture of air and vapor before generation and materially assist the mixing of the air and gas for burning. Since in hydrocarbon-lamps we 75 have a mixture of about fifteen per cent. gas and eighty-five per cent. air, this is of material importance. In gravity-lamps this mixture must be made at the burner and can thus not be as thorough as in my lamp. I secure a 80 more intimate mixture and a corresponding more combustible compound, which insure a more perfect, instantaneous, and thorough combustion and materially increases the heating and illuminating power over that obtainable in gravity-lamps.

Figs. 12 and 13 are two sections of a combined T and valve for use in a lamp, in which 61 is a T, in which the opening connecting the part of the T at right angles is reduced to a 90 small passage 62 and has crossing it a conical-shaped hole adapted to be closed by a like-pointed valve 63, the T also having a stuffing-box 64, substantially as shown, arofind the valve-rod 65.

Fig. 15 illustrates a special form of needle-point for a needle-valve. In this, 65 is the valve-stem, made of some comparatively-cheap metal, as brass, 66 the valve-cap, having a small hole therein, and 67 the needle, adapted to pass through the opening in the cap and keep the same clear of carbon. My improvement consists in inserting a needle 67, of aluminium, German silver, or other non-corrosive metal, in the valve-stem, where both 100 are large enough to make a good joint, and in making the point of the needle of the curved form shown to give it sufficient strength to stand up under its work.

Fig. 11 shows a modification consisting of 110 putting two of the curved tubes 1 together to form a double lamp. One or more of these tubes may be added to form a lamp of three or more burners. Especial attention in both cases is called to the easy curve of the gas-tube 1, there being absolutely no sharp angles to check the flow of the gas.

While I have shown and described in this specification a series of parts adapted to be used together in a lamp, I wish it distinctly 120 understood that in so showing them in combination I do not thereby limit myself to the use of all of them at the same time, and I also make this application with the distinct understanding that if at any time I desire to 125 cut out any part or change any detail such omission or change shall not affect those claims of the patent in which said parts or details were not embodied.

The broad idea of a vapor-conducting pipe 130 adapted to carry the burner and arranged with its other end in alinement with a needle-valve generator is described and claimed in my pending application, Serial No. 719,601,

filed June 6, 1899. I therefore do not in this application claim that idea; but

What I do claim, and desire to secure by Letters Patent of the United States, is—

5 1. In a lamp of the character described as a drop extension, the combination with a stationary pipe leading from the storage-reservoir and having a stuffing-box on its lower end adapted to slide inside a sliding pipe, of the said sliding pipe connected to the lamp, a stuffing-box on the upper end of the said sliding pipe adapted to slide on the stationary pipe, a collar on the upper end of said sliding pipe and a latch on the said stationary pipe to engage with the said collar and positively support the said sliding pipe in its raised position, substantially as shown and described.

2. In a lamp of the character described the combination with a stationary pipe leading from the storage-reservoir, and a sliding pipe encircling the said stationary pipe, of stuffing-boxes on the said pipes to make the same gas-tight and means of locking the sliding pipe when it is in a raised position consisting of an annular collar on the sliding pipe, a bell-crank catch pivoted on the stationary pipe a spring to force said catch to engage the said collar and a cord fastened to the end 30 of said bell-crank to swing the catch out of engagement with said collar on the sliding pipe, substantially as shown and described.

3. In a lamp of the character described, as a mixing-chamber, the combination with a suitable gas-supply and a gas-chamber in line therewith, of a cylindrical chamber revolvably mounted on the gas-supply pipe and the gas-chamber, and having its axis at right angles thereto, said chamber having one or 40 more of its ends perforated, and means of opening and closing said holes to regulate the supply of air substantially as shown and described.

4. In a lamp of the character described as a mixing-chamber, the combination with a suitable gas-supply and a gas-chamber in line therewith, of a cylindrical chamber revolvably mounted on the gas-supply pipe and the gas-chamber and having its axis at right angles thereto, said chamber having one or more of its ends perforated and having cylindrical disks rotatably mounted thereon, said disks having perforations adapted to be rotated into and out of register with the perforations 55 in the ends of the said chamber to regulate the supply of air substantially as shown and described.

5. In a gas-lamp, having an incandescent mantle, as a burner, the combination with a gas-pipe terminating in a vertical section, of a short section of pipe slipped thereover, an inverted-cup-shaped piece, terminating in a horizontal portion for the chimney to rest on, made integral therewith, lugs on the under 65 side of the said horizontal portion to hold the chimney-clips and the mantle-support, perforations in the said cup-shaped portion and

means regulating the opening of the perforation to regulate the supply of air, of a perforated cap having a deflecting-plate to throw the flame against the mantle, and corrugations around the outside of the cap to steady the mantle and permit access of air inside same substantially as shown.

6. In a gas-lamp, of the incandescent type, the combination with the mantle, means of suspending said mantle, a gas-pipe terminating in a straight section centrally located with reference to said mantle, a perforated cap, corrugated around its outer edge, placed on the end of said pipe, having a centrally-depressed portion to direct the flow of gas to the said holes and through them toward the surrounding mantle so that the flame will strike the mantle, of an inverted-cup-shaped portion adapted to hold the chimney, and the mantle-support, and having holes therein to permit access of air to the flame and means of regulating the supply of air consisting of an exteriorly close-fitting sleeve having perforations adapted to be rotated into and out of register with the holes in the cup-shaped portion and a bead around its lower edge to serve as a means of rotating it substantially as and for the purposes set forth.

7. In a lamp of the generator type the combination with a burner, a chimney thereon and a generator extending across above the chimney of a metal deflecting-cap resting on the chimney below the generator, said cap consisting of a cylindrical metal tube slightly larger in diameter than the chimney and having ears turned in to rest on the chimney, the upper part of said deflecting-cap being flattened to concentrate the hot gases from the burner on the generator substantially as shown and described.

8. In a lamp, as a shade-holder, the combination with a chimney having a contracted upper end, of a flat band of metal formed into a ring of slightly-larger diameter than the said chimney, of lugs integral with said ring, extending downward below said ring, and resting on the chimney where it enlarges, a portion of said lugs being extended out radially from the ring and having clips fastened thereon substantially as and for the purposes set forth.

9. In a lamp of the character described the combination with a suitable frame, a suitable burner and a generator thereover, of a hollow tube at one side thereof under the top of said frame and a fluid-receptacle slidably mounted therein substantially as and for the purposes set forth.

10. In a lamp of the character described, as an initial heater, the combination with a suitable frame, a suitable burner and a generator over the said burner, of a hollow chamber fastened to the under side of the top of said frame and a hollow receptacle filled with a non-combustible wool saturated with a combustible, slidably mounted therein, substantially as and for the purposes set forth.

11. In a lamp of the character described the combination with a suitable generator, a curved vapor-conducting pipe having its upper end in alignment with said needle-valve 5 generator and its other end bearing the burner, and a mixing-chamber connecting the generator and the vapor-conducting pipe, of an air-operated reservoir situated above the said generator and pipes connecting the reservoir and the generator, said reservoir consisting of a hollow receptacle having a central tube passing therethrough, said tube having an opening near its upper end through which passes one end of a small tube, which tube 10 terminates in a vertical portion in the center of the larger tube and has its other end near the bottom of the oil-receptacle substantially 15 as and for the purposes set forth.
12. In a vapor-lamp, the combination with a reservoir, a generator, a mixing-chamber and a vapor-conducting pipe in alignment with said generator and carrying at its other end a suitable burner situated beneath the generator of an extension-drop pipe leading 20 from the reservoir to the generator, the said extension comprising a stationary pipe with a stuffing-box on its lower end, a pipe, connected to the lamp, sliding thereon, having a stuffing-box and a collar on its upper end 25 and an adjustable latch to engage the said collar, substantially as and for the purposes set forth.
13. In a vapor-lamp the combination with a suitable oil-reservoir, a generator, a mixing-chamber and a vapor-conducting pipe having its upper end in alignment with the generator and its lower end carrying the burner situated beneath the said generator 30 of a sliding extension having upper and lower stuffing-boxes, a collar on the upper end of the sliding pipe and an adjustable latch engaging the said collar on the pipe leading from the reservoir to the generator substantially as and for the purposes set forth.
14. In a vapor-lamp, the combination with an oil-reservoir, and a drop extension leading from the reservoir, said extension consisting of a stationary pipe leading from the storage-reservoir, a sliding pipe inclosing the 45 said stationary pipe, stuffing-boxes on the said pipes to make them gas-tight and means of locking the sliding pipe when it is raised, consisting of an annular collar on the sliding pipe, a bell-crank catch to engage the said
- collar and a spring to hold said catch in engagement with the annular collar, of a generator, a vapor-conducting pipe carrying a burner on its lower end and a similar pipe opposite the said vapor-pipe to form the frame for the lamp, and the burner, substantially 55 as described.
15. In a vapor-lamp the combination with an oil-reservoir, a drop-extension pipe leading from the reservoir, a valved vapor-generating pipe, a vapor-conducting pipe, and a 60 burner thereon situated under the said generating-pipe, of a cylindrical mixing-chamber revolvably mounted on the end of the said generator and the vapor-pipe in alignment therewith having its axis at right angles to 65 the axis of the generating-pipe and the vapor-pipe and having its ends perforated with means of opening and closing the perforations to regulate the supply of air, substantially as shown and described. 70
16. In a vapor-lamp the combination with a source of supply, a drop-extension pipe, a valved generating-pipe, a vapor-conducting pipe a mixing-chamber connecting the generating-pipe and the vapor-conducting pipe, 75 a burner situated on the vapor-pipe and beneath the generating-pipe, and a chimney on the said burner, of a cap on the chimney to direct the heat against the generating-pipe, said cap consisting of a cylindrical metal tube 80 slightly larger in diameter than the chimney, having ears turned in to rest on the chimney, the upper part of said cap being flattened to concentrate the flow of gases on the generator, all arranged substantially as and for 85 the purposes described.
17. In a lamp of the character described, as a mixing-chamber, the combination with a suitable gas-supply and a gas-chamber in line therewith, of a chamber revolvably mounted 90 on the gas-supply pipe and the gas-chamber, said chamber having one or more of its ends perforated, and means of opening and closing said holes to regulate the supply of air, substantially as shown and described. 95

In testimony whereof I have signed my name to this specification in the presence of two subscribing witnesses.
